UNITED STATES PATENT OFFICE

WALDEMAR F. STUEWE, OF MILWAUKEE, WISCONSIN

APPARATUS FOR FORMING MANHOLE TOPS

Application filed July 20, 1928. Serial No. 294,257.

This invention relates to a method and apparatus for forming man-hole tops of concrete, or similar blocks.

In forming man-hole tops, it is the usual practice to make them conical and to finish the top of the man-hole off with bricks so as to secure the requisite taper. In addition to this, it is preferable to form the top of the man-hole with one side vertical and with the other side of varying tapers or slants, so that the man hole can readily carry a ladder on its interior straight side.

This invention is designed to provide a novel method and apparatus for forming man-hole tops and to provide a method whereby individual, distinct blocks are formed and are numbered in a regular sequence during the forming operation, so that they may be reassembled to produce the truncated conical shape desired.

Further objects of this invention are to provide a novel form of mold for producing the concrete blocks so that although each block may be distinct and separate from each other, nevertheless it is numbered in a regular sequence so that its exact position may be readily ascertained and the block cemented in place in its regular order so that the exact shape originally intended may be secured.

Further objects are to provide a very simple method and apparatus for accomplishing the results enumerated above and in which the apparatus may be cheaply produced and easily operated, and in which the method may be readily followed.

An embodiment of the invention is shown in the accompanying drawings in which:

Figure 1 is a vertical sectional view through the finished man-hole top, such view corresponding to a section on the line 1—1 of Figure 2;

Figure 2 is a plan view of the man-hole top with parts broken away;

Figure 3 is a vertical sectional view through one of the molds, such view corresponding to a section on the line 3—3 of Figure 4;

Figure 4 is a plan view of the structure shown in Figure 3.

The man-hole top consists of a series of rings of concrete blocks, such rings being in-

dicated by the reference characters *a*, *b*, *c*, and *d* in Figures 1 and 2. These rings are formed of individual blocks. For instance, these rings may be formed of individual blocks, the uppermost ring, for example, being formed of the blocks numbered 34 to 28, such numbers being formed in the blocks themselves. Obviously, other insignia could be used to individually indicate the block and its correct position relative to the other blocks. The blocks are each of different shape from the succeeding block and consequently each block occupies one and only one distinct position in the assembly. This positioning of the blocks is most easily obtained by following the regular sequence of numbering thereon.

Each block is preferably formed with a projecting tongue 1 which fits into a corresponding depression 2 formed in the adjacent face of the succeeding block, as shown in Figure 2. The blocks are cemented in place in any suitable manner by ordinary mortar, cement, or other binding agent, such material being indicated by the reference character 3 in Figures 1 and 2.

It is to be noted that one side of the finished top is straight and that the other side is slanting. This is desirable as it facilitates the placing of an iron ladder within the man-hole, such ladder being omitted for the sake of clearness.

The mold for producing the blocks consists of a series of rings forming successive, truncated, conical sections of decreasing diameters. These successive molds are provided with either the same or different numbers of blocks. Preferably, there are four pairs of rings formed to cast the successive tiers, *a*, *b*, *c*, and *d*. The bottom tier could be, in the form shown, ten blocks, the next tier, nine, the next tier, eight, and the uppermost tier, seven.

The rings or mold for casting the uppermost tier are shown in Figures 3 and 4. The uppermost ring is indicated by the reference character 4, and the innermost ring by the reference character 5. The outermost ring is preferably split at diametrically opposite points and is provided with angle iron lips 6 through which the retaining bolts 7 may pass.

The innermost ring may be continuous, as shown in Figure 4.

Between the rings, radial division plates 8 are removably positioned and held in place by means of pins 9 which extend through the rings and into the plates, as shown most clearly in Figure 3. Obviously, other means may be employed for removably securing or retaining the division plates in place. The rings, when in assembled position, are placed upon bottom plates 10 (see Figure 4). The bottom plates are provided with a plurality of raised numbers 11 which are formed backwards so that the numbers in their correct position are formed in the blocks themselves.

The blocks are cast in an inverted position, as indicated in Figures 3 and 4. After the blocks have been cast and preferably before they are completely hardened, the pins 9 are removed and the innermost ring slipped upwardly from the blocks. This removal may be readily accomplished as the innermost ring slopes outwardly and upwardly and consequently freely draws from the blocks.

Thereafter, the outermost ring, separated into two parts, is removed from the blocks. Subsequently, the division plates are removed, preferably after the blocks have become somewhat more hardened. There is one bottom plate provided for each tier or ring of blocks and the appropriate numbers are carried by the bottom plates.

It will be seen that a very simple method of casting concrete blocks and forming the tops of the man-holes has been provided, and it will be seen further that this method can be followed without requiring any block and tackle or framework of any kind over the top of the excavation for the man-hole.

The blocks are of relatively small weight so that they may be easily handled by the mason without requiring any framework or block and tackle.

It will be seen further that the apparatus for forming the blocks is of extremely simple and cheap construction, and that it may be used with the utmost ease.

Although the invention has been described in considerable detail, such description is intended as illustrative rather than limiting as the invention may be variously embodied and as the scope of such invention is to be determined as claimed.

I claim:

1. A mold for concrete blocks comprising an inner and an outer ring-like member arranged in spaced relation, substantially radial division plates located between said members in spaced relation to each other, and means for temporarily holding said plates in position, both said ring-like members being conical and said outer ring-like member being split.

2. A mold for concrete blocks comprising an inner and an outer ring-like member ar-

ranged in spaced relation, substantially radial division plates located between said members in spaced relation to each other, and means for temporarily holding said plates in position, both said ring-like members being conical and said outer ring-like member being split, said division plates having a flute therein to produce a depression at one end of one block and a corresponding projection at the other end of the next adjacent block.

3. A mold for concrete blocks comprising an outer and an inner ring-like member having sides making different angles with reference to the vertical, division plates between said ring-like members, and base plates upon which said ring-like members are adapted to rest, said base plates having means thereon for forming a different insignia in each block cast between the ring-like members and the division plates.

4. A mold for concrete blocks comprising an outer and an inner ring-like member having sides making different angles with reference to the vertical, division plates between said ring-like members, and base plates upon which said ring-like members are adapted to rest, said base plates having means thereon for forming successive members in the blocks cast between the ring-like members and the division plates, whereby the blocks may be readily reassembled in their correct order.

5. A mold for concrete blocks comprising an inner and an outer conical ring-like member arranged in spaced relation, substantially radial division plates located between said members in spaced relation to each other, and means for temporarily holding said plates in position.

6. A mold for concrete blocks comprising an inner and an outer conical ring-like member arranged in spaced relation, substantially radial division plates located between said members in spaced relation to each other and means for temporarily holding said plates in position, said division plates having a vertically disposed flute therein to produce a depression at one end of one block and a corresponding projection at the other end of the next adjacent block.

7. A mold for concrete blocks comprising an inner and an outer ring-like member having sides making different angles with reference to the vertical, division plates between said ring-like members and base plates upon which said ring-like members are adapted to rest.

In testimony that I claim the foregoing I have hereunto set my hand at Milwaukee, in the county of Milwaukee and State of Wisconsin.

WALDEMAR F. STUEWE.
